UNITED STATES PATENT OFFICE.

CHARLES W. ARMBRUST, OF CRYSTAL LAKE, ILLINOIS, ASSIGNOR OF ONE-FOURTH TO
SYDNEY STEIN, OF CHICAGO, ILLINOIS.

BRAKE-SHOE.

1,010,009.

Specification of Letters Patent. Patented Nov. 28, 1911.

Application filed January 18, 1911. Serial No. 603,267.

To all whom it may concern:

Be it known that I, CHARLES W. ARMBRUST, a citizen of the United States, residing at Crystal Lake, in the county of Mc-
5 Henry and State of Illinois, have invented new and useful Improvements in Brake-Shoes, of which the following is a specification.

This invention relates to brake shoes, and 10 my present embodiments relate more particularly to that type or class of brake shoes known as "interlocking" shoes, wherein the back and face of the shoes are provided with interlocking means, whereby a partially worn shoe can be detached from the head and applied to the wearing face of a new shoe, so that the partially worn shoe 15 may be completely used up.

One of the novel features of my present 20 invention resides in a construction wherein the interlocking parts on the back and face of the shoe respectively are of such a character that two similar shoe bodies or one whole shoe body and another partially worn 25 shoe body can be brought into interlocking relation by placing the bodies with the face of one against the back of the other, and giving them a slight relative longitudinal movement, so as to bring the interlocking 30 parts into co-operative relation. In the present invention the interlocking parts are so constructed and arranged that the shoe bodies may be interlocked by imparting a relative longitudinal movement to the bodies 35 in either direction, that is, when the bodies are properly positioned with the face of one against the back of the other, they may be interlocked by moving one of the bodies 40 relatively to the other longitudinally in either direction. This construction permits the shoes to be secured on the brake head with either end uppermost and obviates the necessity of positioning one end of the 45 shoe always at the top, thereby enabling the shoes to be reversed if desired, and also insuring the locked relation of the bodies, irrespective of which end is disposed/uppermost on the brake head.

Another feature of my invention consists 50 in eliminating the usual guide and thrust lugs which are ordinarily provided to engage with the end prongs of the brake head for the purpose of preventing the shoe from becoming displaced or thrown out of alignment. In lieu of the usual thrust and guide

lugs I have equipped the back of my improved shoe with a plurality of transversely arranged ribs, spaced from the centrally disposed attaching lug a sufficient distance to enable the attaching lugs of the brake 60 head to be positioned between these ribs and the attaching lug on the shoe, so that the sides of the lugs of the brake head will be engaged by said transversely disposed ribs and the ends or sides of the attaching 65 lug of the shoe thereby preventing the shoe from being displaced or thrown out of alignment.

Other novel features of construction and 70 many of the objects and advantages of this invention will be apparent as it becomes better understood from the following description when taken in connection with the accompanying drawings, illustrating preferred embodiments thereof. 75

Referring to the drawings,—Figure 1 is a side elevation of a brake shoe embodying my invention, the shoe being shown as attached to a brake head; Fig. 2 is a top plan view of one form of my improved shoe; Fig. 3 is a bottom view thereof; Fig. 4 is a view similar to Fig. 1, showing a modified form of the shoe; Fig. 5 is a sectional elevation on the line 5—5 of Fig. 4; Fig. 6 is a sectional elevation on the line 6—6 of Fig. 4; Fig. 7 is a detailed fragmentary sectional 80 view on the line 7—7 of Fig. 4, showing one locked position of the means for locking two shoe bodies together; and Fig. 8 is a view similar to Fig. 7, showing another 85 locked position of said locking means. Fig. 9 is a fragmentary plan view of the central portion of a shoe showing the shape of the central locking shoulder.

On the drawings, 10 designates the main 90 body of the shoe on the back of which and disposed centrally thereof is provided a projecting shoulder 11 (Fig. 5). The central portion 12 of the side walls of this shoulder is disposed at right angles to the base 13 of the shoulder, while the end portions 14 of the walls are undercut to form a dove-tail connection with a detachable undercut attaching lug 15 or with the recess on the face of a similarly shaped shoe. The side walls 105 of a centrally disposed recess 16, with which a shoulder constructed as above described is adapted to interlock, are undercut at 17 in the center and adjacent the ends of the walls, leaving between such undercut portions 110

straight portions for the insertion of the undercut portions 14 of the shoulder. It will be evident that after such shoulder has been inserted into the recess, the bodies may be moved longitudinally in either direction to effect locking engagement between the shoulder and the undercut walls of the recess. Such relative longitudinal movement will dispose the undercut end portions of the shoulder in interlocking engagement with one end and the centrally undercut portion of the side walls of said recess.

Spaced from the locking shoulder 11 and upon either side thereof, I have provided 15 transversely arranged ribs 18. These ribs are adapted to perform the function of the usual guide and thrust lugs in preventing displacement of the shoe and maintaining the same in proper alignment, and also to 20 space one shoe away from another shoe when interlocked.

From Fig. 1 it will be apparent that the attaching prongs 19 of the brake head 20, which is of a well known type, fits snugly 25 between the sides of the shoulder 11 and the transverse ribs 18. The close engagement between the prongs 19 and the ribs 18 will prevent the body of the shoe from twisting relatively to the head sufficiently to be 30 thrown out of alignment. It will be evident that this construction obviates the usual guide and thrust lugs which customarily engage with the end prongs 21 of the brake head for the purpose of maintaining the shoe 35 in alignment.

Upon and integral with the back of the shoe and between the ends thereof and the ribs 18, I have provided locking lugs 22 of a general shape and contour shown in Figs. 40 2, 7 and 8. The portions 23 of the side walls of these lugs are disposed vertically with respect to the back of the shoe, while the parallel portions 24 and the tapering portions 25 are undercut for the purpose of effecting 45 interlocking engagement with suitably shaped recesses provided on the face of a similar shoe body. In addition to the centrally disposed recess 16 which has been previously described, the face of the shoe is provided 50 with recesses 26 of the same general shape and contour as the locking lugs 22, with which the side walls of the recess interlocking engage. The wider portion 27 of these recesses has vertical side walls while the narrower portion 28 and the tapered portion 29 has undercut side walls for engagement with the undercut portions 24 and 25 respectively 55 of the locking lugs 22.

When it is desired to attach a new or a 60 partially worn body to the face of a new shoe on the brake head, the back of the body to be attached is so positioned against the face of the other body that the wide portion of the locking lugs 22 between the undercut walls 24 will slip into the recess 26

between the vertical walls 27 thereof, the tapered portions of the lugs slipping into the tapered portions of the recesses. If now the movable body member or in other words, the member to be attached, be moved longitudinally of the new member toward the right, viewing Figs. 1, 4 and 7, the undercut portions 24 and 25 of the lug 22 at the right end of the shoe will lockingly engage with the undercut walls 28 and 29 respectively of the corresponding recess 26, while the undercut walls 24 of the lug 22 at the opposite end of the body will lockingly engage with the undercut walls 29 of its respective recess 26. This relative longitudinal movement of the body members will also bring the undercut portions 14 of the shoulder 11 into locking engagement with the undercut portions 17 of the walls of the centrally disposed recess 16.

Should the body members be moved relatively in the opposite direction from that above indicated, the undercut portions 24 of the lug 22 at the right end of the body will engage with the undercut walls 29 of the recess 26 in the relation shown in Fig. 8, while the lug and recess disposed at the opposite ends of the members will lockingly engage in the position shown in Fig. 7.

It is thus apparent that when the locking lugs are inserted into their respective recesses, the body members may be rigidly locked together by moving said members relatively and longitudinally in either direction.

As shown in Fig. 1 the ends of the back of the removable shoe body lie flat against the ends of the face of the fixed shoe, while the central portions of the shoe are spaced some little distance apart, the ribs 18 on the old shoe acting as spacing ribs to insure this separation of the bodies, and the ribs 18 on the new shoe acting as combined guide and thrust lugs to cooperate with the central fastening lug of the brake head. One of the advantages of spacing the central portions of the shoes resides in the fact that it is unnecessary to socket the central part of the face of the shoe to any great depth in order to accommodate the shoulder 11, thus permitting a thinner shoe to be employed 110 and insuring greater transverse strength than would be secured were the face of the shoe deeply socketed at this point.

In Fig. 4 the ends of the bodies at their back are provided with spacing ribs 30 which also insure separation of the shoes throughout their length, thereby reducing the depth of the recess 26 and proportionately increasing the strength of the shoes at this point. In this modification of the 125 shoes, the ribs 18 are necessarily somewhat longer than the ribs shown in Fig. 1, which construction not only decreases the depth of the central recess or socket 16 but also insures a more rigid engagement and greater 130

resisting strength between the lugs 19 and the ribs 18.

While I have shown and described embodiments of my invention, which at the present time seem to be preferred, it will nevertheless be obvious that slight changes and variations in the form and dimensions of the parts herein shown and described can be made without departing from the spirit 10 of the invention or sacrificing any of the material advantages thereof.

I claim:

1. A brake shoe comprising a body member provided with an attaching lug, and 15 transversely disposed ribs spaced from said attaching lug, said lug and ribs forming transverse bearing faces to engage the transverse faces of the brake head attaching prongs whereby the brake shoe is maintained in alinement.

2. A brake shoe comprising a body member provided with an attaching lug, and ribs arranged on either side of said lug, said lug and ribs being adapted to engage the 25 transverse faces of the brake head attaching prongs to maintain the brake shoe in alinement.

3. A brake shoe comprising a body member having an attaching lug, and transversely disposed spacing ribs elevated above the back of the shoe to provide transverse bearing surfaces adapted to engage with the holding prongs of a brake head and prevent displacement of the brake shoe.

35 4. A brake shoe comprising a body member having a centrally disposed shoulder arranged upon the back thereof, said shoulder being adapted for the attachment thereto of an attaching lug, transverse ribs disposed upon either side of said shoulder, and locking lugs disposed between said ribs and the ends of the shoe.

5. An interlocking brake shoe comprising a body member formed with intermediate 45 and end locking recesses in its face, intermediate and end locking lugs on the back of said member, and transversely disposed spacing ribs positioned between said intermediate and end locking lugs.

50 6. An interlocking brake shoe comprising a body member provided upon its back with spacing lugs and locking lugs and provided on its face with locking recesses adapted to receive the locking lugs of a similarly shaped shoe, said spacing lugs serving to space said interlocked shoes apart throughout a portion of their length.

7. An interlocking brake shoe comprising a body member provided on its back with a central locking lug having undercut walls and a pair of locking lugs spaced from said central lug and having undercut walls and having a centrally disposed recess and a pair of recesses spaced therefrom on its 55 face, said recesses being provided with un-

dercut walls, whereby the locking lugs on a similar shoe may be introduced into said recesses and said shoes locked firmly together upon relative longitudinal movement of said shoes in either direction.

8. An interlocking brake shoe comprising a body member formed with a plurality of recesses on its face, the side walls of said recesses providing a plurality of undercut portions, the back of said body member being provided with a plurality of locking lugs, the sides thereof being shaped to form a plurality of undercut portions adapted for locking engagement with the recesses of a similar shoe, whereby the shoes may be locked together upon the introduction of 70 said locking lugs into the recesses by relative longitudinal movement of the shoes in either direction.

9. An interlocking brake shoe comprising a body member having a plurality of locking lugs on its back, the side walls of each of said lugs being undercut adjacent the ends thereof, and a plurality of recesses on its face, the side walls of said recesses being undercut adjacent the ends thereof, whereby upon introduction of said locking lugs into the recesses of a similar shoe, the 75 shoes may be locked together by relative longitudinal movement of the shoes in either direction.

10. An interlocking brake shoe comprising a body member, provided with a centrally disposed locking lug, the side walls of said lug being vertical throughout a portion of their length and undercut adjacent the ends thereof, and a centrally disposed recess on the face of said body member, the side walls of which are undercut at the center and adjacent the ends thereof and 80 vertical between said undercut portions, whereby upon introduction into said recesses of a locking lug on a similar shoe, said shoes may be locked together upon 85 relative longitudinal movement of the shoes in either direction.

11. An interlocking brake shoe comprising a body member having three locking lugs projecting from the back thereof, the side walls of said lugs being undercut 90

throughout a portion of their length, the face of said body member having three recesses into which the locking lugs of a similar member are adapted to project, the side walls of said recesses being undercut 95 throughout a portion of their length to cooperate with the undercut portion of said locking lugs, whereby to lock said members together upon relative longitudinal movement thereof in either direction.

12. An interlocking brake shoe comprising a body member provided on its face with locking recesses and on its back with locking lugs adapted to interlock with the locking recesses of a similarly shaped shoe, 100

said shoe also having on its back transversely disposed ribs adapted to engage with the fastening prongs of a brake head and maintain the shoe in alinement and spacing 5 ribs located adjacent its ends, said transverse and end spacing ribs serving to space the back and face of interlocked shoes apart throughout their length.

13. An interlocking brake shoe comprising a body member provided on its face with locking recesses and on its back with locking lugs whereby similarly shaped shoes may be interlocked upon relative longitudinal movement of the shoes in either direction.

14. An interlocking brake shoe comprising a body member provided on its back with a plurality of locking lugs and on its face with a plurality of locking recesses 20 adapted to receive the locking lugs of a similarly shaped shoe, said lugs and recesses being formed to effect interlocking

engagement of the shoes upon relative longitudinal movement thereof in either direction.

15. An interlocking brake shoe comprising a body member provided with means whereby similarly shaped shoes may be interlockingly engaged upon relative longitudinal movement thereof in either direction.

16. An interlocking brake shoe comprising a solid body member provided on its back with central and end locking lugs and on its face with central and end locking recesses adapted to receive the lugs of a similarly shaped shoe, said lugs and recesses being formed to effect locking engagement of the shoes upon longitudinal movement in either direction.

CHARLES W. ARMBRUST.
